UNITED STATES PATENT OFFICE.

EUGENE TERRY, OF ITHACA, NEW YORK.

DESIGN FOR A FINGER-GUIDE FOR TYPE-WRITERS.

SPECIFICATION forming part of Design No. 22,971, dated December 19, 1893.

Application filed November 20, 1893. Serial No. 491,494. Term of patent 14 years.

To all whom it may concern:

Be it known that I, EUGENE TERRY, a citizen of the United States, residing at Ithaca, in the county of Tompkins, State of New York, have invented and produced a new and original Design for Finger-Guides for Type-Writers, of which the following is the specification, reference being had to the accompanying drawing, in which I show an isometrical view thereof.

The leading feature of my design consists in a raised horizontal bar, the bars intersecting it at cross section, all in the same plane, the outline of which when viewed in elevation will fall within an oval outline.

—a— is the raised horizontal bar, and —b— are the cross bars intersecting bar —a— at substantially right angles.

What I claim, and desire to secure by Letters Patent, is—

The design for a finger guide for typewriters substantially as herein described and shown.

In witness whereof I have hereunto set my hand on this 28th day of July, 1893.

EUGENE TERRY.

In presence of—

TRUMAN NOBLES,

JOHN WELZMILLER.
